UNITED STATES PATENT OFFICE.

ERNST SCHMATOLLA, OF NEW YORK, N. Y.

PRODUCER-GAS-FIRED SHAFT-KILNS.

1,068,175.

Specification of Letters Patent.

Patented July 22, 1913.

Application filed February 23, 1911. Serial No. 610,383.

To all whom it may concern:

Be it known that I, ERNST SCHMATOLLA, a citizen of the German Empire and resident of 150 Nassau street, New York, in the county of New York and State of New York, have invented certain new and useful Improvements in Producer-Gas-Fired Shaft-Kilns, of which the following is a specification.

10 This invention relates to gas fired shaft kilns, and is particularly characterized by the coaction of a pair of shaft kilns with one calcining shaft of large diameter, that is formed with and extends from a pre-heating shaft of still larger diameter.

In the accompanying drawings Figure 1 represents a vertical section of the invention, Fig. 2 shows a fragmentary top plan view of the kilns, Fig. 3 is a section as on the line 20 3, 3 of Fig. 1, Fig. 4 represents a section as on the line 4, 4 of Fig. 1, and Fig. 5 shows a section as on the line 5, 5 of Fig. 1.

The kilns of the invention are represented with the charging and pre-heating shaft *b* 25 having the peep and poke holes *v*, formed in its wall *b*¹ and casing *b*². A double roof comprising the plates *c* with the charging opening *d* covers the shaft *b*. A door *e* with the dampers *f* are located over the opening *d*. 30 A preliminary calcining shaft *a* of smaller diameter than the shaft *b* leads from the latter, and has formed in its wall *a*¹ and lining *a*² the peep or poke holes *v*¹.

The shaft *a* connects with the pair of oblong shaft kilns *i* having each formed therewith at their lower ends the discharging hoppers *g*. In the lining *i*² of the shaft kilns are formed the peep or poke holes *v*², *v*³. Openings *w* in the shaft kilns may be used 40 either as poke holes or gas inlets, and poke holes *w*¹ are provided in the lower portions of the said shafts *i*.

The main outside walls of the invention are represented at *a*³ with the recesses *a*⁴ 45 having the projections *t* for the doors *u*. The spaces between the lining *i*² and doors *u* constitute heat retaining chambers *s*.

Poke holes *p* with the covers *p*¹ are formed in the walls *a*³ with the lining *p*². Chambers *q* connect the poke holes *p* with the shaft kilns *i*. Gas conduits *r* lead from the poke holes *p*. Poke holes *v*⁴ extend from the recesses *a*⁴ to the chambers *q*.

A partition wall *k* with the openings *y* 50 separates the kiln shaft *i*. It has the tapered upper portion *k*¹ with the flat top face

*k*². The lower portion of the wall *k* has formed therewith the arches *m*, *m*, that form roofs for the chamber *l*. Gas inlet openings *o* extend through said wall *k* and lead into the chamber *l*. Water pipes *y*¹ are located in the wall *k*. A V shaped division wall *n* extends up into the chamber *l*. Drawing chambers *h* are located being the discharging hoppers *g*, and below the latter are supported grate bars *h*¹ on the supporting bars *h*². Cars *z* below the chambers *h* are used for collecting the heated material. Gas mains 10 have outlets 12 for the openings *o*. Branch pipes 15 and 16 extend from the gas mains 10 and lead to the conduits *r*.

It is to be noted that the area of the cross-section of the shaft *b* is greater than that of the shaft *a*, also that the area of the cross-section of the shaft *a* is greater than the combined areas of the cross-sections of the two shaft kilns *i*. The kilns *i* are shown oblong, but may be rectangular, elliptical, or of other suitable cross-section.

To use the invention the charge of material to be calcined or operated upon is introduced through the opening *d* and the gas, preferably producer gas, from the gas mains 10 is led to the chamber *l*, and to the chambers *q* if the conduits *r* are formed in the walls of the apparatus. Water is at the same time circulated through the pipes *y*¹ to prevent the overheating of the wall *k*. When the products of combustion rise through the charge the greatest heat is retained in the oblong shaft kilns where the final calcination takes place. The next greatest temperature is obtained in the shaft *a* for the preliminary calcination and finally the products of combustion practically give up their remaining heat to the material in the preheating shaft *b*. The increased amount of material met by the gases and products of combustion as they rise, obtains the novel result of the invention.

When the material reaches the discharging hoppers *g* it is a finished product having been gradually reduced or calcined in its descent down the apparatus. The flat top face *k*² of the wall *k* allows some of the charge to bear thereon, and avoids the burning and injury of the top portion of said wall. The dampers *f* control the draft through the kilns so as to regulate the pressure of the gases therein, to equally distribute the same through the charge.

Having described my invention what I

desire to secure by Letters Patent and claim is:

1. The combination of a pair of shaft kilns, a calcining shaft leading to the shaft kilns and of greater area of cross-section than the combined cross-sections of said shaft kilns and a pre-heating shaft leading to calcining shaft of larger cross-section than the latter.
2. The combination of a pair of shaft kilns, a calcining shaft leading to said shaft kilns, a pre-heating shaft leading to the calcining shaft, a partition wall between the shaft kilns having openings for the introduction of gas, a chamber under the partition wall connecting with said openings and said shaft kilns.
3. The combination of a pair of shaft kilns, a third shaft leading to both of said shaft kilns, and of greater area of cross-section than both of the latter, a fourth shaft leading to the third shaft and of greater area of cross-section than the latter, a partition wall between the shaft kilns having openings for the inlet of gas, water circulating pipes extending through the said

wall, a chamber below the wall connecting with the shaft kilns, and a V shaped division wall extending up in said chamber.

4. The combination of a pair of shaft kilns, a third shaft leading to both of said shaft kilns, a fourth shaft leading to the third shaft, a roof over the fourth shaft having an opening, a door over the opening, a pair of dampers for said door, outer walls for the shaft kilns, a lining for the shaft kilns adjacent to the outer walls, a partition wall formed in said lining between the shaft kilns and having openings for gas, a chamber under the partition wall connecting with said openings, poke holes formed in the outer walls, chambers in said lining connecting with said poke holes, and gas conduits connecting with said poke holes.

Signed at Louisville, in the county of Jefferson and State of Kentucky this 21st day of February A. D. 1911.

ERNST SCHMATOLLA.
